FIG. 2.

INVENTOR

Molly M. Cohen

UNITED STATES PATENT OFFICE

106,081

DESIGN FOR A NEGLIGEE

Mollye M. Cohen, New York, N. Y.

Application August 4, 1937, Serial No. 70,826

Term of patent 3½ years

To all whom it may concern:

Be it known that I, Mollye M. Cohen, a citizen of the United States of America, residing in Manhattan, county of New York, and State of New York, have invented a new, original, and ornamental Design for a Negligeé, of which the following is a specification, reference being had to the accompanying drawing, forming part thereof, wherein,

The characteristic feature of my design resides in the combination on the negligeé as shown, of the slide fastener, which extends down the full length of the sleeves, as shown.

I claim:

The ornamental design for a negligeé, substantially as shown, and described.

MOLLYE M. COHEN.
